ELECTRICAL SIGNALING SYSTEM AND
DEVICE THEREFOR

William R. M. Very, Philadelphia, Pa.

Application April 27, 1936, Serial No. 76,584

3 Claims. (Cl. 177—311)

This invention relates to improvements in electrical signaling systems and devices therefor, and has for its object the provision of a system whereby the condition of an electrical circuit may be indicated by either visual or audible means, or a combination of both such means.

Another object of the invention is to provide a device of the above character whereby the condition of an electrical circuit may be indicated at 10 a remote point.

A further object of the invention is to provide an electrical signaling device comprising a compact unit structure which may be used in a variety of places, such for example as in the tail-light of an ordinary automobile, and where, in the event that the regular lamp should fail, an auxiliary lamp will be automatically switched into circuit while at the same time an audible signal will be given.

20 The invention consists substantially in the construction, combination, location and relative arrangement of parts, all as will be more fully hereinafter set forth and as shown by the accompanying drawing and finally pointed out in 25 the appended claims.

From the following specification, it will be evident that the signaling device herein disclosed may be used in a large variety of circuits and that the main circuit, hereinafter termed the 30 "work circuit" may include one or more lamps, a motor or other electrically operated device, or a plurality of signal lights, relays or other devices such as used in street lighting circuits, railway circuits or in fact in circuits where electrical 35 apparatus and devices are used, and that the auxiliary circuit, hereinafter termed the "tell-tale" circuit may be equipped with a lamp or annunciator, drop any other means to give a visual signal, and that any suitable means for 40 producing an audible signal may be used, or a combination of both visual and audible signals may be employed in the tell-tale circuit.

It will also be obvious that the signaling device may be employed with any suitable source 45 of power, depending on the apparatus or device located in the work circuit, and that through simple relay mechanism of any well-known character, the tell-tale circuit may be operated from a local source of current other than the power 50 source.

As such modifications are well known, they are not described herein.

For the sake of illustration, the invention will be described generally as applied to work circuits 55 containing lamps and more specifically in con-

nnection with a unitary device adapted to be plugged into a lamp socket of the ordinary tail light of an automobile.

In the accompanying drawing:

Figure 1 is a schematic diagram of an electrical 5 signaling system embodying the invention and employing an electromagnetic relay for actuating the tell-tale circuit;

Figure 2 is the system, same as Figure 1, but employing a thermostatic switching mechanism; 10

Figure 3 is a system similar to that shown in Figure 1 except that the relay is included in shunt with a resistance serially included in the main circuit;

Figure 4 is a diagram of a system similar to 15 Figure 3, except that a thermostatic switch is used to actuate the tell-tale circuit;

Figure 5 is a top view of a self-contained unit device embodying the invention, and particularly adapted for use in the tail light of an automobile; 20

Figure 6 is a sectional view on the line 6—6 of Figure 5; and

Figure 7 is a view of the unit device shown in Figures 5 and 6 plugged into the lamp socket in 25 an ordinary automobile tail light, the casing of said lamp structure being shown in section.

In Figure 1, the numerals 10 and 11 denote the conductors of a work circuit which may extend from the apparatus to some distant point and which may include any electrical device such as a lamp 12. Conductor 10 may be connected through the terminal 13 via conductor 14 to a suitable source of current such as a battery 15 which is connected via a terminal 16 to a winding 17 of a relay generally denoted by the numeral 18 having an armature 19 and a contact 20. 30

The armature 19 is connected to one side of the winding 17 and via a conductor 21 is connected to a terminal 22 to which is connected the conductor 11 of the work circuit. 40

As shown in the figure, a circuit may be traced in which the battery 15, the work circuit, the lamp or other device 12 and the winding of the relay 17 are included in series. The relay is therefore 45 actuated, the armature 19 being drawn away from contact 20 as long as the circuit through the device 12 is intact.

Assuming that the work circuit is broken by reason of any failure therein or in the device 12, 50 obviously current will momentarily cease to flow through the winding 17 of the relay, and consequently the armature 19 will be released and will close against contact 20.

A circuit may now be traced from the battery 55
